UNITED STATES PATENT OFFICE.

AUGUST C. SCHNAKE, OF CENTRALIA, ILLINOIS.

WEATHER STRIP.

Application filed May 5, 1925. Serial No. 28,116.

The invention relates to weather strips particularly adapted in connection with doors or hinged windows, and has for its object to provide a device of this character comprising a member secured to one side of the door and extending inwardly in a recess in the lower end of the door, and outwardly and terminating in a horizontally disposed flange overlying the upper side of a horizontally disposed flange carried by a member secured to the outer side of the door, and which last named horizontally disposed flange limits the downward movement of the sill plate engaging member, but at the same time allows said sill plate engaging member to frictionally bind on the sill plate.

A further object is to form the sill engaging member from relatively strong spring material, for instance spring bronze for insuring a water tight engagement of the longitudinally disposed rib with the sill plate.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a vertical transverse sectional view through the lower end of a door and the weather strip.

Figure 2 is a front elevation of a portion of the door and the weather strip.

Figure 3 is a detail perspective view of portions of the weather strip, showing the same in position to be assembled.

Referring to the drawing, the numeral 1 designates a conventional form of door, and 2 the sill thereunder. Secured to the upper side of the sill by means of screws 3 is a longitudinally disposed plate 4, with the convex surface 5 of which the weather strip cooperates. The underside of the door 1 is provided with a longitudinally disposed channel 6, with which the horizontal portions 7 of the weather strip member 8 engages. The portion 7 at its outer end is provided with an upwardly extending flange 9, which is secured to the side of the door 1 by means of nails 10. The portion 7 at its

inner end terminates in a downwardly inclined flange 11, which flange at its lower end terminates in a longitudinally disposed bead 12, which engages the curved convex surface 5 of the plate 4 and forms a watertight and weathertight frictional joint. Flange 11 beyond the bead 12 extends upwardly and terminates in a vertically disposed flange 13 in a plane outside the door and is provided with an outwardly extending horizontally disposed flange 14, which overlies the inwardly extending horizontally disposed flange 15 of the downwardly and outwardly extending plate 16, secured to the side of the door by means of the screws 17. It will be seen that when the door is open the flange 14 will engage the flange 15, and the downward movement of the flange 14 will be limited, and by providing the overlying flanges 14 and 15, the strip carried by the lower end of the door may be formed from relatively heavy or strong spring material for insuring a positive frictional engagement of the bead 12 with the sill plate 4 for positively excluding water and air, and overcoming objectionable noises in weatherstrips of this character incident to wind vibrating the same.

From the above it will be seen that a weatherstrip is provided for doors and hinged windows, which strip is positive in its operation, may be formed from relatively heavy spring material, the parts reduced to a minimum, and one which may be easily and quickly applied to a door, and constructed in a manner whereby the plate engaging strip will be limited in its downward movement.

The invention having been set forth what is claimed as new and useful is:—

The combination with a door, a sill plate disposed beneath said door, of a weatherstrip, said weatherstrip comprising a member disposed in the channel of the door, said member at its inner end terminating in a downwardly, outwardly and upwardly extending flange, a downwardly struck longitudinally disposed bead carried by said flange within the door channel and frictionally engaging the sill plate, the outer end of the downwardly, outwardly and upwardly extending flange terminating in a vertically disposed flange to one side of the door adjacent the door channel, a hori-

zontally disposed flange carried by the vertically disposed flange and extending outwardly, a member secured to the side of the door and inclining downwardly and outwardly, said last named member terminating in an inwardly extending horizontally disposed flange underlying the first men-

tioned horizontally disposed flange, and forming means for limiting the downward movement of the horizontally disposed flange when the door is in open position. ¹⁰

In testimony whereof I affix my signature.

AUGUST C. SCHNAKE.
